UNITED STATES PATENT OFFICE

CHARLES WARD HALL, OF BUFFALO, NEW YORK

METALLIC CONSTRUCTION FOR AIRCRAFT AND THE LIKE

Application filed August 26, 1929. Serial No. 388,408.

This invention relates primarily to a metallic construction, of the type shown and described in Letters Patent No. 1,609,468 issued to me under date of December 7, 1926, in which sheet metal, preferably duralumin or other suitable aluminum alloy, is largely employed and in which a framework of transverse and longitudinal members is enclosed, in part or wholly, by a structural skin.

In constructions of this character, which are well adapted for such parts as the wings and fuselages of airplanes and the hulls of seaplanes and of light racing hydroplanes for example, it has heretofore been the practice to first assemble the framework and then to fit and attach the sheet metal skin by riveting it to the outer chords or flanges of the frame members, usually to the more closely spaced stringers or longitudinal members of the frame. The riveting of the skin to the framework, however, is rather a tedious operation, requiring time and labor, and frequently is troublesome because of the difficulty of access to the work.

The principal object of my present invention is to simplify the work, and so cheapen the cost, of the construction; and this object I have attained by a new method of construction which, departing from the old procedure, consists, broadly stated, in attaching to the skin suitably positioned thereon one set of the frame members, usually and preferably the longitudinal stringers, as the first step in the operation and in then fitting and attaching these members, carrying the skin thereon, to the transverse frames or other such frame members.

The great advantage of this method of procedure is that the major part of the riveting required, for the attachment of the skin to the stringers, can be done on riveting machines or as a machine operation, and the special handwork required, for riveting the stringers in place on the transverse frames, is not only less in amount than formerly but is more accessible for the use of suitable portable riveting machines.

The invention also includes the novel features of structural detail hereinafter de-

scribed and particularly pointed out in the appended claims.

For a full understanding of the invention and of its several features, reference is made to the accompanying drawings, in which—

Figure 1 is a view showing, in perspective, a broken section of the hull of a sea-plane in process of construction; Fig. 2 is an enlarged perspective view of a clip for use in the attachment of the stringers to the ordinary frames; and Fig. 3 is an enlarged detail, partly in side elevation and partly in section, of a jointure by which the tubular inner chord of a stringer is carried through a bulkhead frame.

As here illustrated, the framework of the structure comprises a keel A, frames B, bulkhead frame B', and stringers C; and D indicates the structural sheet metal skin with which the framework is enclosed.

The sheet metal keel A, of truss construction, is stiffened along its lower outer edge by strips 1 riveted to its opposite sides, its central or web portion is stiffened by riveting to the opposite sides thereof flanged semi-tubular web members or U-sections 2, and to its upper edge, provided with spaced notches 3 to receive the inner tubular chords of the frames, is attached a chord member 4 of flanged tubing which is riveted in place after the frame chords have been inserted in the notches therein and closes these notches.

Each of the frames B, also of sheet metal construction, is provided with a flanged chord 5 around its outer edge, which edge is provided with spaced notches 6 to receive the inner tubular chords of the stringers, and to its inner edge is riveted a continuous chord 7 of flanged tubing. The web portion and outer flange of the frame is cut apart, centrally of the bottom, to admit the keel and, when in place with its tubular chord resting on the bottom of a notch in the keel, these severed ends are secured to the keel by angles 8 or by flanges bent up from the web material.

The bulkhead frame B', stiffened by flanged semi-tubular upright U-sections 9 riveted to its opposite sides, is provided with a double or T-flange around its outer edge by

means of shaped angles 5^a riveted thereto, but is without notches in this edge, and around the edge of a central opening, which provides a passageway therethrough and is to be closed in any suitable manner by a water-tight door (not shown) is riveted a chord member 7^a of flanged tubing. The keel is, or may be, carried through the bulkhead by slitting the plate (not shown) to receive the web of the keel and joining the sides of the slit to the keel by angles similar to the angles 8, and carrying the upper tubular chord of the keel, plugged at this point, through an opening provided therefor and packing and closing the opening around the chord by a clip similar to the clips 11 by which the stringers are attached to the ordinary frames, as hereinafter described.

The stringers C are here shown as of bulb angle form, with outer flange, a solid web, and inner tubular chord. They are placed in position on the inner side of the sheet metal skin D, or a section thereof, in suitable spaced relationship to enable them to fit into the spaced notches 6 in the frames and their flanges are riveted to the skin, preferably, as in my prior patent, with the heads of the rivets countersunk in the outer surface of the skin in conical depressions upset both in the skin and in the flanges of the stringers. As a matter of practice, it will be found convenient to attach the stringers to the skin successively first positioning one stringer and running the parts through a riveting machine which will form the depressions, punch the holes, and insert and set the rivets, and repeating the operation with each successive stringer.

The stringers having been secured to a section of skin and the frames having previously been attached to the keel, the stringers with the skin thereon are fitted into the notches in the frames and there secured in place by suitable clips 10 (see Fig. 2), which are or may be shaped up from sheet metal to provide a circular flanged opening 11 adapted to embrace the tubular chord of the stringers and two wings or ears 12 which straddle and are riveted to the web of the stringers, while the body of the clip is riveted to the web of the frame. The clips may be attached to the stringers either before or after the stringers have been fitted into place in the notches of the frames; but, where attached in advance as here shown, the stringers will either have to be fitted into the notches in position to allow the clips to pass the flanges on the outer edges of the frames and then shifted slightly therein to bring the body of the clips against the web of the frame, or, better, so attached that what may be called their flat backs will abut against the side of the frames opposite that from which the flange projects. The skin, on each side of the keel, is bent downwardly to provide a flange 10,

and the flanges of the two sections of skin on the opposite sides of the keel with packing and a U-shaped cover-strip are riveted together through the keel, as in my prior patent. At other points, adjacent sections of the skin may be overlapped and joined, to form a water-tight or other joint, in any suitable manner.

In the case of a bulkhead frame, the preferred practice is to carry the skin continuously over its flanged edges, but to cut the stringers away, or to use stringer sections of a length, to provide a space 13 sufficient to permit the insertion of the flanges of the frame between the ends of the stringer sections and then to carry the tubular chords of the stringers through openings 14 in the frame by a special jointure (see Fig. 3), which is both water-tight and in effect renders the chords of the stringers continuous throughout. For this purpose a section of tube 15, which preferably is plugged centrally by a cork or other stopper 16 and is telescopically inserted within the tubular chord of one section of the stringer, is shifted longitudinally after the stringer is in place through the opening in the bulkhead frame and through two shaped gland-rings 17, one on each of the frame, and partially into the tubular chord of the adjacent section of the stringer. The flanges of the two rings are then riveted together, through the frame, to compress a packing 18, of tow or other suitable material, between the rings and tightly about the tube. To reinforce the stringer at this point, a short section of stringer 19 is sprung over the stringer proper on each side of the bulkhead and is shifted thereon as close to the bulkhead as possible and then riveted in place both to the stringer and to the skin. The skin should be riveted to the flanges of the angles around the bulkhead through an interposed packing strip.

While I have described the several parts as joined by rivets, I have done so simply because I prefer to use rivets for joining together these parts when made of duralumin or other similar alloys of aluminum, which cannot be successfully spot-welded, and it will be understood that any other means suited to the material used may be employed.

It is evident that the invention is adapted to constructions of the framed and enclosed or partially enclosed, parts of all classes of aircraft, and, generally, to all structures in which a metallic framework rigidly supports and is in turn strengthened by a metallic skin.

It is also to be understood that the several features of the invention may be variously modified in their details and that one or more of these features may be used without the others, within the scope of the appended claims, without departing from the spirit or sacrificing the advantages thereof.

What I claim as new, and desire to secure by Letters Patent, is—

1. In a metallic construction for aircraft and the like having for its primary framework a series of transverse frames and a series of longitudinal stringers extending at right angles and without break of continuity over a plurality of the frames, and a structural sheet metal skin, the method of construction which comprises temporarily supporting the frames in position, positioning the stringers upon and securing them to the skin, fitting the assembled stringers and skin as a unit upon the frames, and attaching the stringers to the frames to permanently secure the frames in position and complete the framework.

2. In a metallic construction for aircraft and the like having a structural sheet metal skin enclosing at least partially a framework consisting of a series of transverse frames and a series of longitudinal stringers extending at right angles and without break of continuity over a plurality of the frames, the method of construction which comprises temporarily supporting the frames in position, positioning the stringers upon and securing them to the skin, fitting the skin and attached stringers upon the frames, and completing the structure by securing together the frames and stringers.

3. In a metallic construction for aircraft and the like having a structural sheet metal skin enclosing at least partially a primary framework of transverse frames and longitudinal stringers extending at right angles and without break of continuity over a plurality of the frames, the method of construction which comprises temporarily supporting the frames in position, attaching a series of stringers to each of a plurality of skin sections, fitting the assemblage of stringers and skin sections upon the frames, permanently securing the frames in position by rigidly fastening the stringers thereto, and joining together the adjoining sections of the skin.

4. In a metallic construction for aircraft and the like having a framework with keel and transverse frames and longitudinal stringers and a structural skin, the process which comprises joining the keel and transverse frames, shaping up the stringers from sheet metal and attaching a series thereof to each of a plurality of skin sections, fitting the assembled stringers and skin sections upon and attaching the stringers to the frames, and joining together the adjoining sections of the skin.

5. In a metallic construction for aircraft and the like having a framework of transverse frames and longitudinal stringers and a structural skin, the process which comprises attaching a series of stringers to a section of skin, then attaching a series of clips to the

stringers, and attaching the said assembly to the frames by means of the clips.

6. In a metallic construction for aircraft and the like having a framework of transverse frames and longitudinal stringers and a structural skin, the process which comprises fastening the stringers to the skin in suitably spaced relationship thereon, then fitting the stringers into spaced slots provided therefor around the peripheries of the frames, and finally securing the stringers in place by clips.

7. In a metallic construction for aircraft and the like having a framework of transverse frames and longitudinal stringers of bulb angle form and a structural skin, the process which comprises fastening the flanges of the stringers to the skin in suitably spaced relationship thereon, then fitting the inner bulb chords of the stringers into spaced slots provided therefor around the peripheries of the frames, and finally securing the stringers in place by clips encircling the bulb chords of the stringers and attached to the webs of both stringers and frames.

8. The method of constructing a metallic structure framed by transverse frames, including a bulkhead, and longitudinal stringers and at least partially enclosed by a structural skin which comprises attaching to a section of skin adapted to extend continuously over the bulkhead and adjoining frames on each side thereof a series of stringers suitably positioned thereon and cut away at the position of the bulkhead to admit the same, attaching the stringers with the attached skin to the frames other than the bulkhead, and joining the adjacent ends of the cut away stringers through openings in the bulkhead and sealing the openings around the stringers with a water-tight packing.

9. The method of constructing a metallic structure framed by transverse frames, including a bulkhead, and longitudinal stringers of bulb angle section and at least partially enclosed by a structural skin which comprises attaching to a section of skin adapted to extend continuously over the bulkhead and adjoining frames on each side thereof the flanges of a series of stringers suitably positioned thereon and cut away at the position of the bulkhead to admit the same, inserting the stringers thus attached to the skin in notches provided therefor in the outer periphery of the frames other than the bulkhead and attaching them to said frames, and joining the adjacent ends of the cut away stringers through openings in the bulkhead by telescopingly fitting the ends of sections of tubing passed through said openings into the ends of the tubular chords of the stringers and sealing the openings around the tubing with a water-tight packing.

10. In a metallic construction of the type described, the method of connecting the tubular chord of two sections of one frame mem-

- ber through a second member which comprises providing an opening in the second frame member in alignment with the tubular chord of the sections of the first member, telescopically inserting a length of tubing passed through said opening into the adjacent ends of the tubular chord of the sections of the first member, and then sealing the said opening around the tubing with a water-tight packing. 70
11. In a metallic construction having a plate and adjacent the opposite sides of the plate the ends of two sections of a member provided with a tubular chord, a jointure for the chord of the two sections comprising a section of tubing passing through an opening in the plate and telescopically fitted into the end of the chord of each of the two sections, and a water-tight packing sealing the opening in the plate around the tubing. 75
12. In a metallic construction having a plate and adjacent the opposite sides of the plate the ends of two sections of a member provided with a tubular chord, a jointure for the chord of the two sections comprising a centrally closed section of tubing passing through an opening in the plate and telescopically fitted into the end of the chord of each of the two sections, and a water-tight packing sealing the opening in the plate around the tubing. 80
13. A sheet metal clip for metallic constructions of the type described having a body provided with a substantially circular opening open at one side to the side of the body by a slit and, upset from the body on one side thereof, a flange surrounding said opening and providing substantially parallel ears along the sides of said slit. 85
14. In a metallic construction for aircraft and the like with a framework having a keel and transverse frames, the process of joining the keel and frames which comprises forming the lower chord and web of the keel, slotting the upper edge of the web of the keel at the frame positions to receive the upper chords of the frames, cutting apart the web and lower chord of the frames centrally to straddle the web of the keel, fitting together the keel and frames, closing the slots in the web of the keel over the chords of the frames by attaching a chord member to the upper edge of the web of the keel, and joining the ends of the webs of the frames to the web of the keel. 90
15. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 95
- CHARLES WARD HALL. 100
16. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 105
17. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 110
18. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 115
19. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 120
20. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 125
21. In a metallic construction for aircraft and the like having a framework with a keel and transverse frames, a jointure between the keel and a frame in which the lower and upper chords of the keel are continuous below and above the respective chords of the frame and the web of the keel is continuous through the web of the frame, the upper chord of the frame is continuous through an opening therefor in the upper part of the web of the keel, and the ends of the lower chord and web of the frame adjoining the sides of the web of the keel are joined thereto. 130
